US00D868087S

(12) **United States Design Patent** (10) Patent No.: **US D868,087 S**
(45) Date of Patent: ** *Nov. 26, 2019

(54) **DISPLAY SCREEN OR PORTION THEREOF
WITH GRAPHICAL USER INTERFACE**

- (71) Applicant: **Apple Inc.**, Cupertino, CA (US)
(72) Inventor: **Bas Ording**, San Francisco, CA (US)
(73) Assignee: **Apple Inc.**, Cupertino, CA (US)
(*) Notice: This patent is subject to a terminal disclaimer.
(**) Term: **15 Years**
(21) Appl. No.: **29/629,089**
(22) Filed: **Dec. 11, 2017**

Related U.S. Application Data

- (63) Continuation of application No. 29/566,343, filed on May 27, 2016, now Pat. No. Des. 805,099, which is a continuation of application No. 29/498,760, filed on Aug. 7, 2014, now Pat. No. Des. 757,791, which is a continuation of application No. 29/418,272, filed on Apr. 13, 2012, now Pat. No. Des. 710,877, which is a continuation of application No. 29/354,641, filed on Jan. 27, 2010, now Pat. No. Des. 660,864.

CLAIM

The ornamental design for a display screen or a portion thereof with graphical user interface, as shown and described.

DESCRIPTION

The FIGURE is a front view of a display screen or portion thereof with graphical user interface showing the claimed design.

The outermost broken lines in the FIGURE show a display screen or portion thereof, and form no part of the claimed design.

1 Claim, 1 Drawing Sheet
